UNITED STATES PATENT OFFICE.

WILLIAM G. MACKAY, OF WORCESTER, MASSACHUSETTS.

PUMP SUCTION STRAINER.

Application filed August 28, 1920, Serial No. 406,541. Renewed June 10, 1922. Serial No. 567,461.

To all whom it may concern:

Be it known that I, WILLIAM G. MACKAY, a citizen of the United States, residing at Worcester, in the county of Worcester and 5 State of Massachusetts, have invented new and useful Improvements in Pump Suction Strainers, of which the following is a specification.

This invention relates to an attachment 10 for pump strainers, the principal object of the invention being to provide means for automatically scraping the exterior of the strainer every time the pump is used.

Another object of the invention is to provide 15 a cylinder formed of a plurality of scraping blades which surround the strainer with means for attaching the cylinder to the suction valve in such a manner that when the valve is raised the cylinder will be 20 partly rotated to cause the blades to pass over the perforated walls of the strainer to scrape foreign matter therefrom.

Another object of the invention is to provide 25 spring means for holding the valve in closed position and for returning the scraper cylinder to its normal position, thus the scraper cylinder will be given a partial rotation in one direction when the valve is raised and will be rotated back to its normal 30 position by the spring means while the valve is being lowered.

This invention also consists in certain other features of construction and in the combination and arrangement of the several 35 parts, to be hereinafter fully described, illustrated in the accompanying drawings and specifically pointed out in the appended claims.

In describing my invention in detail, reference 40 will be had to the accompanying drawings wherein like characters denote like or corresponding parts throughout the several views, and in which:

Figure 1 is a side view showing the 45 strainer end of the pump with my invention applied thereto.

Figure 2 is a longitudinal sectional view through Figure 1.

Figure 3 is a bottom view.

Figure 4 is a cross section on line 4—4 50 of Figure 1.

Figure 5 is a cross section on line 5—5 of Figure 1.

In these views 1 indicates the lower end 55 of the pump or pipe to which the pump is attached and 2 indicates the strainer cyl-

inder which is attached to this end, this cylinder being provided with rows of perforations as shown at 3. 4 indicates the foot valve which is placed in the pipe 1 immediately above the strainer and the stem 5 of this valve is extended through the strainer. This stem is made in the form of an Archimedean screw, the end of which passes through a clearance hole made in the bottom 60 of the strainer. The valve is provided with wings 6 which engage the longitudinally extending guides 7 for preventing turning movement of the valve while permitting it to be moved vertically under the action of the 65 pump.

The scraper cylinder 8 is formed of a hub 9 having an opening therein snugly engaging the screw so that the hub will be caused to rotate by the screw passing through it, 75 and the radiating arms of blades 10 which have rightangularly extending parts 11 which engage the sides of the strainer cylinder, the arms or blades 10 engaging the bottom of the strainer. A coiled spring 12 80 is placed around the lower end of the screw and said spring bears against the hub 9 and a washer 13 is held on the screw by the nut 14 which engages the screw threaded end of said screw. This spring will hold the 85 valve upon its seat and when said valve is raised by the suction of the pump the stem will also be raised and as this stem passes through the hub it will cause the scraper cylinder to be partly rotated thus causing 90 the blades to scrape the walls of the strainer cylinder and when the suction stroke of the pump is completed the spring will return the parts to normal position so that the scraper cylinder is rotated in an opposite 95 direction. Thus the side walls and bottom of the strainer cylinder will be kept clean and the perforations kept free of foreign matter so that the liquid may freely pass into the cylinder. I prefer to provide a 100 blade for each row of perforations. As the spaces between the blades are vertically arranged the matter scraped off the strainer by the blades will drop by gravity from said spaces.

The invention is adapted to be used on all forms of reciprocating pumps for handling dirty fluids which are liable to choke an ordinary strainer, such as bilge and donkey pumps aboard ships, and those used in coal 110 mines, factories and the like. This invention will be found extremely advantageous

for use on ship pumps as its use will render unnecessary the engineer or his attendant diving into the filthy bilge water to clean choked strainers.

- 5 It is thought from the foregoing description that the advantages and novel features of my invention will be readily apparent.

I desire it to be understood that I may make changes in the construction and in the 10 combination and arrangement of the several parts, provided that such changes fall within the scope of the appended claims.

What I claim is:

1. In combination with a pump and its 15 strainer, a foot valve above the strainer, a cylinder surrounding the strainer and formed of a plurality of scraping blades and means for oscillating the cylinder on the strainer by the movement of this foot valve.

20 2. In combination with a pump and its strainer, a foot valve for the pump, a stem thereon passing through the strainer and twisted to produce an oscillating screw, a

cylinder surrounding the strainer and 25 formed of a plurality of scraping blades and a hub, said hub engaging the screw and spring means for holding the foot valve in closed position.

3. In combination with a pump and strainer, a foot valve above the strainer, 30 means for preventing rotary movement of the valve while permitting vertical movement thereof, a stem connected with the valve and having its lower part formed to provide an Archimedean screw which passes 35 through the bottom of the strainer, a cylinder surrounding the strainer and comprising a hub engaging the screw and radiating blades having rightangularly extending parts at their outer ends for engaging 40 the side walls of the strainer, a coiled spring on the lower end of the screw and a nut and washer for holding the spring between the valves and the hub.

In testimony whereof I affix my signature. 45

WILLIAM G. MACKAY.
